PORTABLE CONCRETE MIXER AND DRIVE
MEANS THEREFOR

George A. Williams, San Antonio, Tex.

Application November 14, 1947, Serial No. 785,969

5 Claims. (Cl. 259—177)

1

This invention relates to concrete mixers, and more particularly to concrete mixers of the portable type.

A main object of the invention is to provide a novel and improved concrete mixing apparatus especially suited for small concrete jobs, whereby instead of employing a large mixing machine and a large number of wheelbarrows to transport the material to and from the mixing machine as is now common practice, individual portable mixing machines are employed to transport the material, said machines being driven from a centralized power source to perform their mixing operations, providing the effect of several concrete mixers all powered by one engine or power source and greatly lessening the time required for mixing.

A further object of the invention is to provide an improved concrete mixing apparatus wherein the output per worker is greatly increased by eliminating the need for conveying the unmixed material in wheelbarrows to a mixer and then re-loading the mixed concrete in the wheelbarrows in order to convey it to the location where it is to be deposited, and wherein the unit cost per yard of concrete is reduced by the greatly increased mixing capacity provided by employing multiple portable mixing units according to this invention.

Further objects and advantages of the invention will become apparent from the following description and claims, and from the accompanying drawings, wherein:

Figure 1 is a side elevational view of a portable concrete mixer shown in engagement with a centralized power source, all in accordance with the present invention.

Figure 2 is a rear elevational view partly in cross-section of the concrete mixing apparatus shown in Figure 1.

Figure 3 is a fragmentary top plan detail view showing the clutch and power transmission means employed on the portable concrete mixing carrier of Figure 1.

Figure 4 is a top plan view of a modified centralized power source for the portable mixer of Figure 1, the drive wheels of three portable mixers being shown in simultaneous engagement with the drive disc of the power source.

Figure 5 is an elevational view, partly in cross-section, of the structure of Figure 4.

Figure 6 is a fragmentary side elevational view, partly in cross-section, illustrating still another form of centralized power means for the portable mixers in accordance with the present invention.

2

Figure 7 is an end elevational view of the structure of Figure 6.

Referring to the drawings, 11 designates generally a portable mixing carrier for concrete, said carrier comprising a mixing drum 12 pivotally secured at 13 for rotation around its longitudinal axis to the cross arm 14 of a U-shaped yoke member 15. The side arms 16, 16' of yoke member 15 are pivotally carried on respective aligned transverse shaft elements 17 and 17'. Indicated at 18 is a frame having parallel depending leg portions 19, 19' and a rearwardly extending U-shaped portion 20. The shaft elements 17 and 17' are respectively journaled in the respective junction portions of the side arms of member 20 with the respective depending leg elements 19 and 19'. Secured to the lower ends of the legs 19, 19' is a transverse axle 21 to the ends of which are journaled the rubber-tired ground-engaging wheels 22, 22' which support the frame 18.

The intermediate portion of drum 12 is formed with an integral peripheral gear 23 which is in mesh with pinion gears, such as shown at 24, carried by the respective transverse shaft elements 17, 17'. Secured to the cross arm of the U-shaped frame element 20 is a vertical post element 25 in the bottom end of which is swivelled a caster 26. Caster 26 has journaled therein the rear ground-engaging wheel 27.

Secured to the frame element 20 and extending rearwardly therefrom is a U-shaped handle bar 28 which is braced at its mid-portion to post member 25 by a strut 29. Secured to the forward end of yoke arm 16' is a hand lever 30, providing a means for tilting the drum 12 around its trunnion supports 17, 17' for discharging material from the open front end, shown at 31 of said drum.

The interior of drum 12 is provided with conventional agitating vanes, not shown, for mixing and kneading the component materials of the concrete responsive to rotation of the drum around its axial pivot 13.

The end portion of shaft element 17 is squared, as shown at 32, and axially slidable thereon is a shouldered clutch sleeve element 33. Sleeve element 33 is formed with an annular groove 34 in which is engaged the depending arms of a conventional shifter yoke 35 carried by the end of a hand lever 36. Hand lever 36 is pivoted to the adjacent side arm of frame element 20 at 37 for rotation in a horizontal plane, whereby the clutch sleeve element 33 may be shifted axially on squared shaft portion 32 responsive to rotation of hand lever 36.

Journalized in a bracket 38 secured to frame element 19 and axially aligned with shaft element 17 is a shaft 39 carrying a shouldered clutch member 40 adapted to be interlocked with clutch sleeve element 33 when said sleeve element is shifted axially as above described. Shaft 39 also carries a sprocket wheel 41 which is coupled by a sprocket chain 42 to a sprocket wheel 43 secured to wheel 22. When clutch elements 40 and 33 are interlocked, rotation of wheel 22 provides driving torque at pinion gear 24 which rotates the drum 12 by the meshing engagement of pinion gear 24 with the ring gear 23.

In operation, the materials are loaded into the drum 12 at the locations where they are stored and the mixer is then pushed to a centralized power source adapted to provide torque at the ground-engaging wheel 22. Lever 36 is then actuated to interlock the clutch elements 40 and 33, causing the drum 12 to be rotated. After a period of rotation sufficient to thoroughly mix the concrete, the clutch elements 40 and 33 are disengaged and the mixer is pushed to the location where the concrete is to be dumped. Discharge of the concrete is accomplished by pivoting the upper end of drum 12 downwardly on its trunnion bearings by means of handle 30 whereby the material may flow out of the open end 31 of the drum. The mixer may then be returned to the source of material to repeat the above described operation.

Referring to Figures 1 and 2, 44 indicates one form of centralized power source which may be employed. Said power source comprises a ramp structure 45 upon which the mixer may be pushed, said ramp portion comprising inclined opposing side elements 47, 47 over which the main wheels 22, 22' may ride and a rear inclined middle element 46 over which the rear caster wheel 27 may ride. Journaled in suitable brackets between the opposing side elements 47, 47 are transverse shafts 48 and 49 carrying the friction rollers 50 and 51. Shaft 48 is connected to a suitable prime mover. Torque is transmitted to the ground-engaging wheel 22 by means of a friction roller 50 carried by shaft 48. The idler rollers 51 support the wheels during the application of torque to wheel 22. The ramp structure 45 may be of substantial length and may be provided with a plurality of identical stations each adapted to receive a mixer thereon, whereby the shaft 48 transmits torque to the ground-engaging main wheels 22 of a plurality of mixers at the same time.

Figures 4 and 5 disclose another form of centralized power means for the mixers. Designated at 52 is a flat base on which is journalized a flat disc member 53 by means of radial roller bearings such as shown at 54. Base 52 is provided with a vertical central bearing shaft 55 and rotatable thereon is a sleeve member 56 centrally secured to disc member 53. At its top end the sleeve member 56 carries a bevel gear 57. Journalized in bearing brackets 58 and 59 secured to base 52 is a shaft 60 carrying a pinion gear 61 which is meshed with bevel gear 57. Shaft 60 is connected to a suitable prime mover, such as a gasoline engine, or the like.

Secured to the support 52 and extending over disc member 53 are suitably spaced upstanding stop brackets 62. Secured to the frame of each mixer forwardly adjacent a wheel 22 thereof is a stop bracket 63. In operation a mixer is pushed to the centralized power means and its wheel 22 is rolled onto disc member 53 so that the front stop member 63 carried by the mixer forwardly of said wheel is placed in abutment with a stop 75 position with respect to said endless belt and

member 62. The clutch lever of the mixer may then be operated to transmit torque to the rotary drum 12 in the same manner as previously described.

In the specific arrangement illustrated in Figures 4 and 5, provision is made for simultaneously operating three mixers. Obviously, by making the rotary disc member 53 larger, more mixers may be operated simultaneously on the disc member from the same centralized power source.

Figures 6 and 7 illustrate still another form of centralized power means for the mixers. Designated at 64 is a base member to which are secured parallel elongated side support members 65, 65. Journalized transversely in the end portions of the side supports 65, 65 are rollers 66 carrying an endless belt 67. Journalized in the side supports at uniformly spaced longitudinal intervals are transverse rollers 68 underlying the upper element of the endless belt 67. The shaft of one of the end rollers 66 is connected to a suitable prime mover.

Secured to the side supports 65, 65 at suitable longitudinally spaced positions thereon are elevated transverse abutment members 69 adapted to be engaged by a front stop member 63 of a mixer when its power transmitting wheel 22 is placed on the belt 67, as shown in Figure 6. Movement of the belt therefore causes torque to be applied to the wheel 22, and by operating the clutch lever of the mixer, said torque may be transmitted to the rotary drum 12 thereof. By making the belt 67 and its supporting structure of suitable length, a plurality of mixers may be simultaneously driven thereby from the same power source.

While certain specific embodiments of a portable concrete mixer apparatus have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A power source for driving one or more portable wheeled concrete mixers of the type having a rotary mixing drum coupled to a ground-engaging wheel of the mixer, comprising a flat support, a flat disc member rotatively mounted in a horizontal position on said support and adapted to support the ground engaging wheel of each of said mixers, a bevel gear carried by said disc member at its center, a power shaft extending substantially radially of the disc member, a pinion gear carried by said shaft and meshing with said bevel gear, and a plurality of stop members carried by said support and projecting upwardly and adjacent said disc member, each of said stop members being spaced angularly around said disc member and adapted to be abutted by a stop member carried by each mixer forwardly of its ground engaging wheel.

2. A power source for driving a portable concrete mixer of the wheeled type having a rotary drum coupled to a ground-engaging wheel of the mixer, comprising an elongated frame, a pair of rollers journalized transversely at the respective end portions of the frame, an endless belt engaged over said rollers and adapted to support the ground engaging wheel of said mixer, means for connecting one of the rollers to a power shaft, and a stop member secured to said frame and extending transversely across the frame in elevated position with respect to said endless belt and

adapted to be abutted by a stop member carried by said mixer forwardly of its ground engaging wheel.

3. A concrete mixer comprising a frame comprising a horizontal U-shaped element disposed with the legs thereof directed forwardly, vertical elements secured to depend from the forward ends of said legs, ground engaging wheels journalled on the lower ends of said vertical elements, a post depending from a rear portion of said U-shaped element, a caster wheel vertically journalled on the lower end of said post, mixer trundling handle means on a rear part of said U-shaped element, a mixing drum supported between the legs of said U-shaped element.

4. A concrete mixer comprising a frame comprising a horizontal U-shaped element disposed with the legs thereof directed forwardly, vertical elements secured to depend from the forward ends of said legs, ground engaging wheels journalled on the lower ends of said vertical elements, a post depending from a rear portion of said U-shaped element, a caster wheel vertically journalled on the lower end of said post, mixer trundling handle means on a rear part of said U-shaped element, a mixing drum supported between the legs of said U-shaped element, a second U-shaped element positioned between said legs with the legs thereof directed forwardly, the legs of the second U-shaped element being journalled on a transverse axis to the forward ends of the legs of the first mentioned U-shaped element, means on an intermediate part of said second U-shaped element mounting said mixing drum on said second U-shaped element for rotation on the axis of the drum, and means operatively connected between one of said ground engaging wheels and

said drum for rotating said drum on its axis as said one wheel is rotated.

5. A concrete handling device comprising a platform having a plane area and another area depressed with respect to said plane area, a pair of horizontal rollers spaced apart at opposite sides of said depressed area, power means for driving at least one of said rollers, a concrete mixer having a rotary drum and a pair of ground engaging wheels at least one of which is operatively connected to said drum, said concrete mixer having another ground engaging wheel, said concrete mixer being positioned on said platform with said other wheel rollably resting upon said plane area and with at least one of the first mentioned wheels positioned between said rollers, said rollers engaging circumferentially spaced points on said one wheel whereby said concrete mixer is prevented from rolling freely upon said platform while said drum is being operated from one of said rollers but said concrete mixer can be rolled off said platform by the exertion of sufficient force thereon to disengage the one wheel from between said pair of rollers.
